(57) **CLAIM**

The ornamental design for a container cover or trivet, as shown and described.

DESCRIPTION

FIG. 1 is a top perspective view of the container cover or trivet according to one embodiment of the present invention;

FIG. 2 is a first end elevational view thereof;

FIG. 3 is a second end elevational view thereof, opposite from the first end elevational view;

FIG. 4 is a side elevational view thereof, with the opposite side view being reversed thereto;

FIG. 5 is a top plan view thereof;

FIG. 6 is a bottom plan view thereof;

FIG. 7 is a cross-sectional view along the line 7-7 in FIG. 5;

FIG. 8 is a cross-sectional view along the line 8-8 in FIG. 5;

FIG. 9 is a top perspective view of the container cover or trivet according to another embodiment of the present invention;

FIG. 10 is a first end elevational view of the container cover or trivet of FIG. 9;

FIG. 11 is a second end elevational view of the container cover or trivet of FIG. 9, opposite from the first end elevational view;

FIG. 12 is a side elevational view of the container cover or trivet of FIG. 9;

FIG. 13 is a top plan view of the container cover or trivet of FIG. 9;

FIG. 14 is a bottom plan view of the container cover or trivet of FIG. 9;

FIG. 15 is a cross-sectional view along the line 15-15 in FIG. 12; and,

FIG. 16 is a cross-sectional view along the line 16-16 in FIG. 12.

The broken lines in the drawings illustrate the portions of the design that form no part of the claim.

1 Claim, 10 Drawing Sheets
